UNITED STATES PATENT OFFICE.

JEAN WAGNER, OF PARIS, FRANCE.

GRATE-BAR.

SPECIFICATION forming part of Letters Patent No. 561,632, dated June 9, 1896.

Application filed May 15, 1894. Serial No. 511,277. (No model.) Patented in France March 28, 1894, No. 237,366; in Belgium March 29, 1894, No. 109,246; in Switzerland April 16, 1894, No. 8,391; in England April 18, 1894, No. 7,702; in Germany April 19, 1894, No. 80,221; in Italy April 30, 1894, No. 36,276; in Spain July 9, 1894, No. 16,041, and in Austria July 16, 1894, No. 3,258.

To all whom it may concern:

Be it known that I, JEAN WAGNER, a citizen of the French Republic, residing at Paris, France, have invented certain new and useful Improvements in Grate-Bars, (for which I have obtained patents in France, No. 237,366, dated March 28, 1894; in Belgium, No. 109,246, dated March 29, 1894; in Switzerland, No. 8,391, dated April 16, 1894; in Great Britain, No. 7,702, dated April 18, 1894; in Germany, No. 80,221, dated April 19, 1894; in Italy, No. 36,276, dated April 30, 1894; in Spain, No. 16,041, dated July 9, 1894, and in Austria, No. 3,258, dated July 16, 1894,) of which the following is a specification.

The object of my invention is to provide a grate in which air can freely circulate, so that it arrives at the fire in a warmer state, the bars at the same time being relatively cool by reason of their structure.

This grate-bar can be applied to all grates without the necessity of any change, and allows of the employment of various kinds of combustibles by use of small coal, coal-dust, coke, charcoal, sawdust, or any other waste; and it consists of certain features of construction to be hereinafter fully described and then claimed.

In the accompanying drawings, Figure 1 represents a side elevation of one end of a grate-bar embodying my improvements. Fig. 2 is a plan view of portions of two bars. Fig. 3 shows a section on the line 3 3 of Fig. 2. Fig. 4 is a similar section of a modification. Fig. 5 represents a perspective view of two members of which the grate-bar is composed. Fig. 6 is a detail view of the rocking mechanism for the grate-bars.

Similar letters of reference indicate corresponding parts.

My improved grate-bar is composed of the two members B B'. Each of these members is formed of a cast-iron plate C, the height of which is about eight-tenths of the height of the whole bar, and on one face of the same, at equal distances apart, are cast the inverted triangular pyramids D, the opposite faces of the same being either plain, as shown in Fig. 3, or channeled, as in Fig. 4, the channels Z

corresponding in number to the pyramids. 50 The bases of these pyramids project above the plate C about two to three centimeters, forming the upper part of the grate-bar. The altitude of the triangular bases of the pyramids is exactly equal to the width of the bar. 55

The grate-bar is formed by connecting the two members B and B' in such a manner that the pyramids D of the one register with the intervals E' formed by the pyramids D' of the other, while the pyramids D' register with the 60 intervals E of member B.

The dimensions of the different members B and B' are such that when once united so as to form one grate-bar they are not able to touch at any single point except where connected at the ends. The triangular abutments F at the sides of the ends of the members prevent all lateral movement of the same, and consequently prevent the members B acting in contact with the members B'. The upper parts of the grate-bars are thus formed by the bases of the pyramids D and D', which are separated from each other by equal and regular spaces G. To maintain the regularity of these spaces, it is only necessary to prevent 75 any longitudinal displacement of the members B and B', and this I attain by making certain parts of the base of one of the pyramids of the member B of such dimensions that it exactly fills out the interval between 80 the two neighboring pyramids of the member B'.

As can be seen, each grate-bar of my system is formed of two members which register one with the other, but without touching each 85 other. The two members have thus between them, toward the lower part, a more or less greater space, by which the air is permitted to penetrate into the interior of the bar and circulate between the different pyramids of 90 said bar. The air is thus thoroughly separated and distributed over the whole surface of the grate-bars by the spaces G between the bases of said pyramids.

The volume of air reaching the combustible 95 material will be much greater with a grate composed of parts as above than in an ordinary grate. The space between the bars can

naturally be much diminished—as, for instance, in an ordinary grate the spaces between the bars being ten millimeters, a distance of three millimeters would be sufficient with my improved grate-bars to insure a greater flow of air to the grate. The diminished distance between the grate-bars will also have the effect to a great extent of preventing the production of dust, ashes, &c. Further, the air is uniformly distributed over the whole mass of combustible material, and it reaches the fire warmer than would be the case with an ordinary grate-bar.

My improved fire-bar has the further important advantage that it can be mechanically raked or cleaned by the employment of a movement entirely suitable to this system of grate-bars.

If an oscillatory movement be imparted to a grate-bar around its axis of support, one attains, besides an oscillatory movement, a shearing movement at its upper part. One of the two members of which the bar is composed rises or falls alternately against the other, the pyramids of one member sliding in the intervals provided by the pyramids of the other member. It is this movement which characterizes my system and which I employ to mechanically rake or clean the grate. It is clear that in imparting an alternative oscillatory movement to all the bars of the grate a series of shearing movements is imparted to the upper parts of the bars, and it is this movement which tends to clean the grate. The grate will thus always be in proper order, the deleterious effects of the heat being less marked, and consequently the grates will be of longer duration. To impart the oscillating movement to the bars, various means may be employed; but I prefer the following as being more simple and practical.

The ends I of either of the parts B B' which go to form a fire-bar A are provided with knife-blade edges and rest in notches or bearings O, provided in the cross-bar K. Below the grate and at about the middle thereof is a transverse bar L, the ends of which extend into the side walls of the fireplace. To facilitate a to-and-fro longitudinal movement of the transverse bar L the ends of the same are not placed directly on the masonry, but slide in cast-iron boxes N, set in the holes M. The upper part of the transverse bar is provided at equal distances apart with teeth P of suitable form, which project either between the bars or between the two members B and B' of the same bar. By imparting a to-and-fro longitudinal motion to this bar L an oscillatory motion is produced in the grate-bars, the members of which consequently slide one upon the other alternately. This transverse movement of the bar L is obtained by means of an eccentric Q, keyed to the end of a shaft R, to which is imparted a rotatory motion, either

continuous or intermittent, in the one direction or the other. This shaft R is supported from one of the side walls by bearings S, fixed in the masonry. On the end of the shaft which passes through the box is mounted a suitable crank, by which the rotatory motion is produced.

The principal advantages of my improved system of grate-bars are, first, for the distance of three to four millimeters between the bars the quantity of air which flows through the combustible material is more than sufficient to obtain complete combustion; further, the air is uniformly distributed over the whole mass of combustible material, permitting of economy in firing and of using up the entire material, however fine; second, the grate-bars present a very large cooling-surface, the air arrives warmer to the combustible material, and all adhesion of slag to the surface is avoided; third, by a very simple and practical means one can, as desired, rake or clean the grate mechanically by employing a movement entirely adapted to the system of bars.

Having thus described my invention, I claim as new and desire to secure by Letters Patent—

1. A grate-bar composed of two plates, disposed parallel with each other side by side and provided on their adjacent faces with triangular inverted pyramids which form downwardly-extending side ribs, the pyramids of one plate projecting into the spaces between the pyramids of the adjacent plate forming vertical air-channels between them, said plates being provided with means for preventing lateral and longitudinal movement of the plates, and being straight on their outer faces whereby they are adapted to form straight channels between the bars when arranged in the grate.

2. A grate-bar composed of two plates disposed parallel with each other side by side and provided on their adjacent faces with triangular inverted pyramids which form downwardly-extending side ribs, the pyramids of one plate projecting into the spaces between the pyramids of the adjacent plate forming vertical air-channels between them, said plates being provided with means for preventing lateral and longitudinal movement of the plates, and being straight on their outer faces whereby they are adapted to form straight channels between the bars when arranged in the grate, said plates having vertical grooves in their outer faces opposite said ribs.

In witness whereof I have hereunto affixed my signature, in presence of two witnesses, this 2d day of April, 1894.

JEAN WAGNER.
